ABRASIVE GRINDING APPARATUS
 Irving G. Winer, 3241 Kentucky Ave. S.,
 St. Louis Park, Minn. 55426
 Filed Nov. 19, 1965, Ser. No. 508,728
 6 Claims. (Cl. 51—144)

This application is a continuation-in-part of my co-pending application Ser. No. 325,284 filed Nov. 21, 1963, for "Cam Finishing Apparatus," now Patent No. 3,222,822 issued Dec. 14, 1965.

This invention relates to abrasive grinding apparatus, one example of which is apparatus for finishing cams and similar parts requiring smoothly finished edge surfaces. The invention is described with particular reference to apparatus for providing edge cams with a highly polished precision finish on their working edge faces, but it will be understood that the principles of the invention as claimed are adaptable to other grinding applications.

The invention is illustrated in the accompanying drawings in which the same numerals are used to identify corresponding parts and in which:

FIGURE 1 is a perspective view of a cam finishing apparatus incorporating the present invention;

FIGURE 2 is a top plan view of the apparatus;

FIGURE 3 is a fragmentary front elevation, partly in section taken on the line 3—3 of FIGURE 2 and in the direction of the arrows, of the finishing portion of the apparatus; and

FIGURE 4 is a fragmentary and enlarged transverse section, on the line 4—4 of FIGURE 2 and in the direction of the arrows.

Referring now to the drawings, the apparatus as illustrated comprises generally a base 10 supporting a frame or standard 11 which in turn supports a flat horizontal top working platform 12. On one side of the apparatus there is mounted a motor 14 supported by a bracket 15 and having a driven shaft 16, to which is attached a drum 17. An endless belt 18 carrying a coating of fine abrasive material on its outer surface is driven by the motor through the shaft 16 and drum 17.

On the top platform 12 of the apparatus, spaced back from the side mounting the motor 14 there is a bracket 19 which supports a rocker arm 21 for pivotal movement on a shaft 20 carried in the bracket. At the opposite end of the rocker arm 21 from its axis of rotation about the pivot 20 there is journaled a spindle 22 for rotation relative to the rocker arm, and preferably for simultaneous reciprocating motion. Shaft 20 and spindle 22 are both preferably journaled in hardened steel bushings for minimum wear and maximum life.

Spindle 22 is rotated by virtue of attachment to the drive shaft of a second motor 23 mounted on a plate 27. The plate is provided with a slot 28 at one end which engages the shaft 20 so as to hold the motor against rotation relative to the rocker arm, so as to impart rotary motion to the spindle.

As described hereinafter, it is desirable that the spindle 22 reciprocate relative to the rocker arm 21 so as to distribute wear uniformly across the abrasive belt 18. One means of accomplishing such reciprocation is provided by a face cam 24 fixed to the spindle 22 for rotation therewith. A rotary cam follower 25 mounted on a shaft supported by a post or bracket 26 mounted on the top of the rocker arm 21 bears against the working face of the cam 24. A plurality of coil springs 30 extending between the plate 27 mounting the motor 23 and posts 29 extending on opposite sides of the rocker arm resiliently and uniformly urge the cam follower 25 against the face of the cam 24 at all times. As the spindle 22 rotates the cam 24 causes the motor 23 and the plate 27 supporting

2

the motor to be urged closer to and farther away from the rocker arm causing reciprocal movement of the spindle relative to the rocker arm.

The cam 32 to be finished is supported at the free end of the spindle 22 on the opposite side of the rocker arm 21 from the motor 23 and reciprocating cam 24. The cam 32 to be finished is secured to the spindle for rotation therewith along with a master cam 31 whose contours are desired to be exactly duplicated in the cam to be finished.

One means by which the master cam and cam to be finished may be mounted for rotation together is shown in FIGURES 3 and 4. A sleeve 33 of brass or other non-magnetic material is fitted with a plurality of longitudinally extending magnets 34 whose ends are co-planar with the ends of the sleeve 33. The cam 32 to be finished and the master cam 31 are butted up against the opposite ends of the sleeve 33 and held there by the attractive force of the magnets. The cams are located and positioned relative to one another by means of a timing pin 35 extending through the sleeve and projecting from the end faces of the sleeve to fit into a locating hole provided in each of the cams for purposes of alignment. The sleeve 33 is secured to the spindle by means of a set screw 36. It will be readily seen that both cams will rotate and reciprocate with the spindle and with each other simultaneously.

A pair of solid stable blocks extend upwardly from the top of the platform. The first of these blocks 38 underlies the spindle and firmly and solidly supports a small diameter pin 37, preferably formed from wear resistant tool steel, spaced below and in approximate vertical alignment with the spindle. This pin 37 functions as a cam follower for the master cam 31. The sleeve 33 and master cam 31 are so positioned on the spindle 22 that as the spindle rotates and reciprocates the edges of the master cam will at all times be in position to be in contact with the pin 37. The effect of this is that the master cam causes the rocker arm, along with the spindle and motor 23 and associated mechanism, to move on the rocker arm pivot up or down depending upon the particular contour of the master cam in contact with the follower pin at any instant.

The other projecting block 40 is spaced from the first and firmly and solidly supports a second static pin 39, desirably formed from hard wear resistant and heat resistant ceramic material, such as alumina or the like. The endless abrasive belt passes over this pin and the edges of the cam 32 to be finished move in contact with the abrasive belt as it passes around the pin and as the cam 32 rotates with the spindle. The pin 39 is in alignment with the master cam follower pin 37 but is of lesser radius by an amount equal to the thickness of the abrasive belt, in order to insure that the cam to be finished will have the exact dimensions as the master cam. Typically, pin 39 may be of the order of $\frac{1}{4}$ inch diameter and may range from about $\frac{3}{16}$ to 1 inch in diameter. As may be seen from the drawings, drive drum 17 is of substantially greater diameter than pin 39, so that the peripheral speed of belt 18 around pin 39 is many times the peripheral speed around the drum. As seen in FIGURE 1, but best seen in FIGURE 4, the path of travel of belt 18 from drum 17 to pin 39 is at a small acute angle relative to the path of travel of the belt from the pin to the drum, and the belt is in contact with the pin surface over more than about $\frac{1}{2}$ of its periphery.

By means of the apparatus of the present invention cam edges have consistently been provided with finishes in the range from 2.1 to 2 micro-inch finish. The apparatus, according to the present invention, is not limited to the finishing of convex contours but has successfully and

consistently finished cams whose surfaces have concave as well as convex contours.

It is apparent that many modifications and variations of this invention as hereinbefore set forth may be made without departing from the spirit and scope thereof. The specific embodiments described are given by way of example only and the invention is limited only by the terms of the appended claims.

I claim:

1. A precision, abrasive grinding apparatus comprising:
  - (A) a stationary supporting frame,
  - (B) a static abrasive web supporting pin mounted at one end on said frame,
  - (C) a drive means mounted on said frame,
  - (D) said drive means being spaced from said static pin and including a cylindrical driven drum, and
  - (E) an endless abrasive web extending tautly in a continuous loop around said static pin to said drive means and around said drum, the path of travel of said web from said drive means to said static pin defining a small acute angle with the path of travel of said web from said static pin to said drive means, and said web being in contact with the surface of said pin over more than about $\frac{1}{3}$ of its periphery.
2. An apparatus according to claim 1 further characterized in that said static pin is of substantially smaller diameter relative to the diameter of said drive drum, whereby rotation of said drum causes rapid movement of said abrasive web over said pin.
3. An apparatus according to claim 2 further charac-

terized in that said pin is from about $\frac{3}{16}$ to 1 inch diameter.

5 4. An apparatus according to claim 1 further characterized in that said static pin is composed of hard wear resistant and heat resistant ceramic material.

5 5. An apparatus according to claim 1 further characterized in that said drive means comprises an electric motor having said drum secured to its driven shaft, the axis of said driven shaft being parallel to the axis of said static pin.

6. An apparatus according to claim 1 further characterized by the presence of a cam follower pin supported from said frame and in axial alignment with said abrasive web supporting pin, said cam follower pin having a radius greater than the radius of said web supporting pin by the thickness of said web, means for holding a cam to be finished and a master cam resiliently against said web and cam follower pin, respectively, and means for moving said holding means and cams relative to said pins.
